UNITED STATES PATENT OFFICE.

HERBERT R. PALMER, OF CLEVELAND, OHIO, ASSIGNOR TO THE PALMER OIL ENGINE COMPANY, OF EAST CLEVELAND, OHIO, A CORPORATION OF MICHIGAN.

EXPLOSIVE-ENGINE.

No. 877,730.

Specification of Letters Patent.

Patented Jan. 28, 1908.

Application filed August 28, 1903. Serial No. 171,041.

To all whom it may concern:

Be it known that I, HERBERT R. PALMER, a citizen of the United States, residing at Cleveland, in the county of Cuyahoga and State of Ohio, have invented a certain new and useful Improvement in Explosive-Engines, of which the following is a full, clear, and exact description, reference being had to the accompanying drawings.

10 The object of the invention is to provide suitable pumping mechanism which will furnish a continuous circulation of motor fluid, and in connection with this circulating system to provide injecting mechanism 15 which will inject a portion of the fluid from said system into the explosion chamber, together with other features of construction which will be more clearly brought out.

The invention may be here summarized 20 as the combinations of parts shown and hereinafter described, whereby these and some incidental results are attained, as set forth in the claims.

Referring to the drawings, Figure 1 is a 25 side elevation of my engine, showing all the parts in their proper relation with respect to each other; Fig. 2 is an end elevation; Fig. 3 is a similar view with a portion of the cylinder and casing broken away to more 30 clearly show the internal parts and also with the feed supply pump in vertical section; Fig. 4 is a top plan view of the engine with the cylinder heads removed; Fig. 5 is a top plan view of the casing together with the 35 pump mechanism; Fig. 6 is a detail view in vertical section to clearly show the construction of the cylinder and piston together with the explosion chamber; Fig. 7 is a sectional view of the air inlet showing its connection 40 with the carbureter for supplying gasoline mixture; Fig. 8 is a detail view of the pump and the valve mechanism for feeding kerosene under pressure to the explosion chamber; Fig. 9 is a detail view of the same mechanism taken from another direction; Fig. 45 10 is an elevation of the cams for operating the feed pumps and Figs. 11, 12, 13 and 14 are sectional views upon the lines indicated in Fig. 10.

50 In the embodiment herein shown the engine has two parallel cylinders A and A¹. Secured to the upper ends of the cylinders is a casing C. This casing is arranged to extend from one cylinder to the other, and is

provided above each cylinder with an explosion chamber c, as shown in Fig. 6. Each explosion chamber c is provided on one side with an inlet valve c¹ adapted to engage a hollow seat c² secured in the casing, and has a stem c³ extending out through the seat c², 55 where it is provided with a suitable cap c⁴ adapted to be engaged by a spring c⁵ which holds the valve upon its seat. To open this valve a lever R is provided which is pivoted to the casing and is secured to a rod r carrying a friction roller r¹, shown in dotted lines in Fig. 3, for engaging a cam r² upon the cam shaft h². Communicating with the opening within the hollow seat c² is a passageway D which has an air inlet valve D¹, arranged to 60 be opened and closed by suitable mechanism hereinafter described. The passageway D is connected with a suitable gasoline carbureter D², the construction of which is not of the essence of my invention, but is simply 65 arranged to supply carbureted air to the port D, when the engine is started, the valve D¹ having been previously closed, therefore 70 a detailed description of the same is not necessary.

The casing C adjacent to each explosion chamber is provided with a sparking device c⁶ adapted to ignite the gasoline mixture as it is drawn in through the carbureter D², 75 through the passageway D and into the cylinder. This sparking device may, however, be thrown out of operation after the engine is under way. On the opposite side of each explosion chamber, to the point where the inlet valve c¹ is located, is an exhaust valve c⁷ shown in dotted lines in Fig. 3. 80 This arrangement of air inlet and exhaust, together with the oil supply valve, in the explosion chamber is peculiarly effective in an engine of this type for the reason that the incoming air tends to cool the exhaust valve and the relation of the oil supply valve, with 85 respect to the air inlet tends to insure the complete saturation of the air with oil. This valve is operated by the usual operating 90 lever S to permit the exhaust to escape from the engine.

At any point in each explosion chamber, preferably at the top, is located a valve and pump mechanism which supply kerosene 105 under pressure to the engine, and this mechanism consists of a valve casing E secured to the valve casing C by means of suitable

bolts e . Rigid with this casing is a pump cylinder e^1 having within the same a piston e^2 , which is held normally in an outward position by means of a spring e^4 bearing 5 against the head e^5 of said piston. Each cylinder e^1 is provided with a boss e^6 at a short distance from the point corresponding to the end of the stroke of the piston, connecting up with the pipes y and y^1 , or the return 10 pipe for the motor fluid. Each boss e^6 is provided with an opening e^8 for receiving the pipes y and y^1 , and are located midway between the limits of the stroke of each piston whereby when each piston makes its 15 complete stroke it will close this opening as it passes the same, and the motor fluid ahead of the piston will be injected into the cylinder. Within the casing E , is a sleeve E^1 secured in said casing in any suitable manner 20 and having in its upper end a plug e^6 which projects down to a point just above an opening e^7 registering with a port e^8 leading to the opening in the cylinder e^1 . A cap E^3 is secured to the upper end of the casing E 25 whereby the sleeve E^1 may be readily removed for any reason, whether it be on account of the blocking of the valve or on account of the carbonization of the charge therein. The lower end of the sleeve E^1 is provided with a tapering valve seat e^9 30 adapted to receive a tapering valve e^{10} which has its stem extending up inside of the sleeve E^1 where it is provided with a coiled spring bearing against a boss e^{11} rigid with said stem, and thus holding the valve e^{10} upon 35 its seat. Perforations e^{12} are provided in this boss for the purpose of permitting the passage of oil therethrough. The sleeve E^1 and the casing are both provided with communicating openings which form a passage 40 e^{13} slanting down toward the lower part of said sleeve. A pipe F connects with this opening e^{13} above the valve e^{10} and into the opening in the sleeve E^1 and delivers kerosene through the same. This pipe is provided 45 with a check valve f , Fig. 5, between it and the main supply pipe f^1 , to prevent the backward flow of the oil. One of these valves is provided for each supply pump and 50 valve mechanism.

Mechanism is provided for maintaining a free circulation of kerosene in the feed pipes y and y^1 whereby it may be readily supplied to the feed pumps, and this mechanism consists of a pump J carried by the crank chamber A^2 and connected with the supply pipes by means of pipes j and j^1 . The pipe j communicates with the pipe X^1 which, at its upper end, (Fig. 5) communicates with the main supply pipe f^1 , while the pipe j^1 leads to the tank, not shown, and from this tank the pipe X leads to the feed pipes y and y^1 . A piston j^2 is arranged to reciprocate within the pump J and is pivotally connected to an eccentric ring j^3 embracing an eccentric j^4

keyed to the exhaust valve operating cam shaft h^2 by means of a removable key j^5 . This key j^5 is arranged so that it may be readily removed and placed in an opening j^6 (Fig. 3) in the eccentric j^4 for the purpose of serving as a crank for rotating said eccentric to operate the pump for supplying kerosene to the feed pumps when the engine is first started, or after the feed pipes have been drained for any reason. Of course if the feed 75 pipes have not been drained then this operation is unnecessary. The pipe j^1 passes to a chamber j^6 in the lower end of the pump and communicates with the chamber j^7 through a valve controlled port j^8 . This chamber j^7 is 80 in direct communication with the pump cylinder and communicates with the feed pipe j through another valve controlled port j^9 .

From the foregoing, it will be seen that as the engine operates the kerosene for operating the same will be forced up through the feed pipes to the upper part of the system. A free circulation of kerosene is maintained in this way through the pipe f^1 and the oil is forced in through the valve casing E into the 90 opening within the sleeve E^1 above the valve e^{10} , but since this valve is held closed by its spring the oil travels up through the openings e^{12} in the boss and out through the opening e^8 , through the pump cylinder e^1 , through the 95 passageway e^3 and back through the pipe X to the supply. This operation continues until the pump piston e^2 is forced inward by devices to be described when it passes the passageway e^3 , closes that means of escape 100 for the oil and forces that part of it which has been entrapped in the pump cylinder and the sleeve E^1 , between the valve e^{10} and its seat e^9 and thereby sprays it into the explosion chamber, the check valve f having prevented 105 the backward flow of the oil through the pipe f^1 . The object of arranging the direction of the supply through the opening e^{13} toward the bottom of the casing and just above the valve, and having a free circulation 110 through this part of the mechanism and out through the by-pass e^3 , is for the purpose of preventing the collection of gases and sediment which might hinder the perfect operation of the valve e^{10} .

Mechanism is provided for operating these pumps e^1 , and also for opening the valve D^1 , and, since these two devices are operated in conjunction with each other, their mechanism will now be described. Mounted in 120 suitable bearings upon the frame is a cam shaft H which has rigid therewith, a broad pinion h , meshing with the driving pinion h^1 secured to the exhaust valve operating cam shaft h^2 driven by the engine shaft. This 125 pinion h^1 conveys continuous rotary motion to the broad pinion h and hence to its shaft and permits the shaft H to be shifted longitudinally without disengaging the two pinions.

Rigid with the shaft H are the cams which 130

operate the feed pumps, one set for each cylinder. The cam h^3 in each set is constructed in a manner such that the operating face tapers down in a longitudinal direction as shown in Figs. 11 and 12, where it is continued in the same direction by the cam h^4 , the highest point of which is the same distance from the center throughout its length, but instead of being arranged in a straight line, it runs spirally for a short distance around the shaft. At the point where this cam stops, is located the cam h^5 which retains the same longitudinal direction throughout its length tapering in the same manner as did the cam h^3 , but smaller in size as shown in the drawing. This cam tapers down to a cylindrical collar h^6 which is also rigid with the shaft H and is engaged by the friction roller of the feed pump operating lever when kerosene is not being used or in other words while the engine is being started or at rest. These cams are all rigid upon the shaft as above stated, and any suitable mechanism may be provided for sliding the shaft longitudinally. Such a device is illustrated by a lever Z swiveled to the same.

Pivoted to the casing are the pump operating levers I , I' , which carry suitable friction rollers at one end for engagement with the cams just mentioned and at the other ends are arranged to engage the feed pump pistons, already described. After the engine is under way or after it has attained speed through the use of gasoline, then the operator shifts the shaft H through the mechanism previously described until the friction roller of each feed pump operating lever rests at the foot of the cam h^3 , when the minimum amount of charge for medium speed will be delivered to the cylinders. The further shifting of the shaft H in the same direction will bring a higher point of the cam h^3 into engagement with the friction roller. This will feed a greater amount of oil to the engine. To retard the speed of the engine, the shaft, H is shifted in the opposite direction, so that the friction roller of each feed pump operating lever will be brought to some point in the length of the spiral cam h^4 . The spirals of these cams are such that they will operate the feed pump operating levers a sufficient amount to inject the charge a little in advance of the completion of the compression stroke of the piston. This necessarily causes the immediate explosion, which, since the piston has not yet completed its stroke as just stated will reduce the speed of the engine. The speed of the engine may be varied within broad limits upon these two cams, but if a further reduction in speed is necessary, the shaft H may be shifted further in the direction last specified, when the extent to which the feed pumps are operated will be varied, the time of admission in this instance representing the maximum

advance in the time of admission of the charge to the cylinder last had upon the spiral cam h^4 .

When the engine is at rest and during the time that it is operating upon gasoline, the valve D^1 is closed by a lever G which is pivoted to the stem d^7 thereof. This lever G is in turn pivoted to the frame at g , and has its bifurcated end projecting out and around the shaft H . Secured to the end of the shaft H , 70 is a flange g^1 forming an abutment for a spring g^2 which bears against a collar g^3 loose upon the shaft H , said collar g^3 bearing against the bifurcated end of the lever G . From this it will be readily seen that when 80 the shaft H is shifted in the direction to bring the friction rollers of the feed pump levers upon the cylindrical collar on the shaft H , the spring g^2 will exert a pressure upon the end of the lever G sufficient to hold the 85 valve D^1 upon its seat, thus causing the air passing into the cylinder to come through the carburetor.

A suitable device is provided upon the engine for cooling the pistons by the air 90 which is set in circulation through the operation of the trunk pistons. For this purpose I provide a webbed pipe K which is connected with the crank chamber of one cylinder and with the crank chamber of the other, so 95 that when the piston descends in one cylinder the air from that crank chamber will be forced through the pipe K to the other crank chamber and in its passage through said pipe it will be cooled by the cooling webs k provided thereon.

Throughout the specification and claims the term kerosene has been used as applied to the fuel by which the engine is operated after it is fairly under way. The invention, 105 however, is not limited to the use of kerosene alone though that, by reason of its cheapness, prevalence, and large number of heat units is the best fuel now known to me, and the term kerosene is intended to include any 110 other heavy hydro-carbon which contains a large number of heat units. The term gasoline has also been used to describe the fluid by which the engine is started, but this too is only by way of example and includes any 115 other light hydro-carbons such as alcohol, benzine, naphtha, etc. which may be used for starting the engine in the manner set forth; the fundamental idea being to first start the engine by the use of a light hydro-carbon 120 and then operate it by the carbon as set forth.

Having described my invention I claim:

1. In an explosion engine, in combination, a cylinder and piston, an explosion chamber 125 upon said cylinder, a valve in said explosion chamber, means for conveying motor fluid adjacent to said valve, an injector-plunger adapted to cross and thereby block the outlet for said motor fluid and at the same time 130

inject an explosive charge of such fluid into said explosion chamber through said valve, and a variable cam for controlling said injector.

- 5 2. In an explosion engine, in combination, a cylinder and piston, a valve controlled casing communicating with said cylinder, conduits communicating with said valve casing for the passage of the motor fluid 10 through said valve casing without entering said cylinder, means for supplying a constant circulation of motor fluid to said conduit, and means for injecting a portion of the fluid therefrom through said valve and into the explosion chamber.

- 15 3. In an explosion engine, in combination, a cylinder and piston, a valve in said cylinder for controlling the admission of the charge thereto, a conduit through which 20 motor fluid may pass, an injector plunger arranged in said conduit and adapted to inject a portion of the fluid into the cylinder through said valve, a variable cam, mechanism connecting said cam with said injector 25 plunger, and means for shifting said cam relatively to said mechanism to vary the injection.

4. In an explosive engine, in combination, a cylinder and piston, a combustion chamber 30 for said cylinder, a valve casing secured to said chamber, a valve in said casing for controlling the admission of the charge to the cylinder, means for maintaining said valve in a closed position, a pump cylinder secured 35 to said valve casing, said pump cylinder and said valve casing being provided with ports whereby there may be a continuous circulation through the cylinder of said pump through said casing, means for supplying 40 motor fluid to bring about such a circulation, and a piston in said pump cylinder and adapted to close the egress port therein and inject a portion of the motor fluid into the cylinder.

- 45 5. In an explosive engine, in combination, a cylinder and piston, a combustion chamber for said cylinder, a valve casing secured to said chamber, a valve in said casing for controlling the admission of the charge to the cylinder, means for maintaining said valve 50 in a closed position, a pump cylinder secured to said valve casing, said pump cylinder and said valve casing being provided with ports whereby there may be a continuous circulation 55 through the cylinder of said pump through said casing, means for supplying motor fluid to bring about such a circulation, a piston in said pump cylinder and adapted to close the egress port therein and 60 inject a portion of the motor fluid into the cylinder, and means for blocking the backward flow of the fluid.

- 65 6. In an explosive engine, in combination, a cylinder and piston, an explosion chamber for said cylinder, a valve in said chamber, a

casing above said valve provided with an inlet for the motor fluid and an outlet therefor, an injector cylinder in direct communication with said outlet from said valve casing, an outlet port leading from said injector cylinder, an injector piston mounted in said cylinder and adapted to close the egress port therefrom and to inject a portion of the motor fluid into the cylinder, and means for maintaining a constant circulation through said valve casing and through 70 said injector cylinder.

7. In an explosive engine, in combination, a cylinder, a pump and valve casing mounted upon said cylinder, a spring for holding said valve closed, means for supplying a continuous flow of oil through said pump and said casing, and means whereby the operation of the piston of said pump may block 80 the flow of said oil and force a portion of 85 the same through said valve.

8. A valve for an explosive engine consisting of a casing adapted to be secured to the cylinder, a valve in the lower end of said casing, a pump, a cylinder secured to said 90 casing, means for passing a continuous flow of oil through said casing and said pump cylinder, and means whereby the operation of the pump piston may block the outlet for 95 said oil and may force a portion thereof through the valve of said casing.

9. A valve for an explosive engine, consisting of a casing adapted to be secured to the cylinder, a valve seat secured within 100 said casing, a valve operating upon said seat, and means for holding said valve closed, a pump cylinder secured to said casing, a piston within the same, means for supplying liquid hydro-carbon above said valve seat, 105 said pump cylinder being provided with a port for conveying away the oil as it flows through said casing and through said pump cylinder, said port being so located that when the piston to said pump is operated it 110 will close said port and force a portion of said liquid into the cylinder through said valve.

10. In an explosive engine, in combination with the cylinder, of a valve casing secured to the same, a tubular valve seat 115 having a tapered opening in the lower end of the same, a pump cylinder secured to said casing and having a port leading from the same to the discharge pipe, a valve within said valve seat, said valve having a tapered 120 head, a boss upon the stem of said valve adapted to slide in said seat and provided with suitable openings through the same, means for holding said valve closed, a port for supplying liquid hydro-carbon to the 125 opening within said valve seat, said piston being adapted to close the port leading from its cylinder and also adapted to force a portion of said liquid hydro-carbon through said valve.

11. In an explosive engine, in combination, a cylinder and piston, a valve casing adapted to communicate with this cylinder, a valve for controlling such communication, 5 means for maintaining such valve in a closed position, a pump cylinder communicating with the valve casing, a piston operating in such pump cylinder, an inlet and an egress port in the pump between the pump piston and the valve casing, the pump piston being adapted to close the egress port and inject a portion of the motor fluid into the cylinder, and means for circulating the motor fluid through the pump cylinder.
- 10 12. In an explosive engine, in combination, a cylinder and piston, a valve casing,
- adapted to communicate with the cylinder, a valve for controlling such communication, a pump adapted to inject fluid into the valve casing, means for circulating the fluid continuously through the passageway from the pump to the valve casing, said pump being adapted to shut off the egress from said passageway when it injects fluid into the casing. 20
- 25

In testimony whereof, I hereunto affix my signature in the presence of two witnesses.

HERBERT R. PALMER.
